UNITED STATES PATENT OFFICE.

BRITTON E. BYRD, OF GASTONIA, NORTH CAROLINA, ASSIGNOR TO MILL DEVICES COMPANY, INC., OF GASTONIA, NORTH CAROLINA, A CORPORATION OF NORTH CAROLINA.

KNOTTER.

Application filed June 22, 1928. Serial No. 287,388.

This invention is an improvement in knotters of the type shown and described in Patents Nos. 1,572,182, February 9, 1926, and 1,599,160, September 7, 1926, and more particularly in a knotter for forming what may be distinguished as a hybrid knot.

In the construction of the patents referred to, the knotter is designed to tie a weaver's knot, that is, a small flat knot which will be least noticeable in the woven fabric.

In tying threads, such as voiles, silks and rayon, wherein the surface coefficient of friction is relatively small, and the fibers are relatively stiff, the ends of the threads at the knot tend to back out, thus to loosen the knot.

In application Serial No. 253,595, filed Feb. 11, 1928, a construction is shown especially adapted for tying this character of silks, wherein an additional loop is made at the cut ends of the threads of one thread about the other, to provide thus a stay or scotch for the said ends.

In this construction, an additional turn of the threads about each other is imparted at one side of the knotter, but the positioning of the threads, the cutting and clamping of one thread by the bill, and the use of an auxiliary shear to sever the remaining thread is substantially the same as in the patents first mentioned.

One of the primary objects of the present invention is the provision of mechanism for tying a knot, which may be described as a hybrid knot, having incorporated therein a scotch or stay.

Another object is the provision in a knotter of this character, of thread positioning means at one side of the bill, for winding the threads about each other more than a turn, and for positioning the threads at the end of the winding operation adjacent each other instead of spaced apart laterally as in the usual construction.

Another object is the provision of mechanism for so positioning the threads at one side of the bill, as to cause the bill to simultaneously clamp and cut both ends of the thread, thus enabling the auxiliary shear to be dispensed with.

With these and other objects in view the invention consists in the construction and novel combination of parts fully described hereinafter, illustrated in the accompanying drawings, and pointed out in the claims ap-

pended hereto, it being understood that various changes in the form, proportion, size and minor details of construction within the scope of the claims, may be resorted to without departing from the spirit of the invention.

In the drawings forming a part hereof:

Fig. 1 is a side view of the improved knotter.

Fig. 2 is a similar view looking at the other side.

Fig. 3 is a plan view.

Fig. 4 is a longitudinal section.

Fig. 5 is a section on the line 5—5 of Fig. 4.

Fig. 6 is a perspective view of the thread positioning means at the commencement of the operation.

Figs. 7 and 9 are similar views showing other steps in the operation of tying.

Fig. 8 is a plan view of the two threads in the position of Fig. 7.

Fig. 10 is a plan view of the completed knot prior to tightening.

In the present embodiment of the invention the improved knotter comprises a suitable frame indicated generally at 1, having a handle 2 and including an operating lever 3, intended to be operated by the thumb.

The tying bill indicated generally at 4, is of usual construction, comprising two fixed and a movable blade, which is operated during the rotation of the bill to cut and clamp one of the threads.

The bill is rotated by means of the lever 3, the said lever having a fork 5, engaging a helical portion 6 of the bill, thereby to rotate the bill when the lever is operated. All of these parts are similar to the parts shown in the patents referred to.

Mechanism is provided at each side of the bill for supporting a pair of threads to be knotted in proper relation with respect to the bill. Such mechanism includes pairs of seats 7—8 and 9—10 respectively, in the side plates of the frame, and when the threads are laid in the seats in parallel relation, as shown more clearly in Fig. 6, one will be on the inner side of the bill, and the other on the outer side, that is, the clamping jaws will extend between the threads which are indicated at 11 and 12, the thread 11 being shown as black, for enabling distinction of the threads.

Mechanism is also provided for moving the outermost thread 11, to the inner side of the innermost thread 12, prior to the op-

eration of the bill. The thread 11 is moved above the thread 12 while at the same time the thread 12 is moved outwardly below the thread 11, so that the threads are crossed on each side of the bill. The moving mechanism includes rockers 13 and 14, respectively, which are pivoted to the side plates of the frame 1.

Each rocker has a pair of seats 15 and 16 for the rocker 13, and 17 and 18 for the rocker 14. Normally the rockers stand so that the seats 7—15, 8—16, 9—17, and 10—18, respectively, register, this position being shown in Fig. 6. A slide 19 is mounted on the side of the frame 1 adjacent the rocker 13, and this slide has a notch 20 in its outer end, which engages the innermost thread 12 at that side in the seats 8—16, and moves the thread outwardly in the crossing operation.

20 A gear sector 21 is pivoted to the frame at 22, and the sector engages a pinion 23 on a stub shaft 24, to which the rocker 14 is rigidly connected to rotate with the shaft. The shaft is journaled in the adjacent side 25 plate of the frame, and in a shield 25, which normally covers and hides the sector, the shield being clearly shown in Fig. 1. The slide 19, previously mentioned, is pivoted to the rocker 13 at its outer end as indicated at 30 26, so that when the slide moves outward to move the thread 12, it operates the rocker 13, and the sector and the slide are operated in unison by means of a cam 27, forming a part of the lever 3 before mentioned. The 35 slide is connected by means of a cross shaft 28 with a slide 29 on the outer face of the opposite side of the frame, and the shaft 28 extends through a slot 30 in the sector.

The arrangement is such that when the 40 shaft 28 is moved longitudinally of the bill toward the operative end thereof, the slides 19 and 29 move therewith, and the slot 30 is so arranged in the sector, that this outward movement of the shaft swings the sector 45 downward, causing it to rotate the pinion 23.

Referring to Figs. 6 to 9 inclusive, it will be noticed that the seat 17 of the rocker 14 is relatively deep, extending beneath the shaft 24, and it will be apparent that the sector imparts an amplified movement to the rocker 14. The relative proportion of the parts is such that the rocker is rotated through substantially two complete rotations, while the rocker 13 is swinging from the position of Fig. 6 to that of Fig. 9. Thus the threads 11 and 12 will be wrapped around each other as shown in Fig. 7, during the operation of the rockers, and before the bill commences the actual operation of tying. It 60 is the amplified movement of the rocker which causes the formation of the character of knot shown in Fig. 10.

The knot is stripped and strained, by a stripping arm 31, which is substantially of the character shown in Patent No. 1,572,182.

This stripper is a lever, pivoted at 32 within the frame, and having a pair of arms 33 and 34, between which one of the fork arms 5 of the lever 3 moves. The lower edge of the arm 33 is concentric with the pivotal connection 35 of the lever, so that the lever 31 is not effective during the forward movement of the fork arm to operate the tying bill until the fork arm nears the end of its forward movement.

As the fork arm reaches the end of its movement, it engages the arm 34 of the lever, and swings the stripper abruptly upward and outward, straining the knot, and stripping it from the bill. Referring to Fig. 4, it will be noticed that the stripper has a notch 36 for engaging the strands to prevent them slipping over the stripper.

The construction so far described, with the exception of the seat 17 in the rocker 14, is 85 the same as that shown and described in my application Serial No. 253,595, filed February 11, 1928. The seat 17, however, in the present construction is deepened, so that when the parts are in the normal position of Fig. 90 6, the bottom of the seat 17 is well below the seat 9. When the rocker commences its amplified movement in the early part of the movement the thread 11 is not engaged by the seat, but at the end of the movement it is 95 carried a less distance than in the construction of the above mentioned application.

Because of this the thread 11 is wrapped about the thread 12 more than a complete turn, and in fact about a turn and a half, and the threads are positioned after the winding operation is in position to be simultaneously clamped and cut by the bill. Thus the auxiliary cutter usually used for cutting the thread 11 may be dispensed with, while at 105 the same time a firm nonslipable knot is produced. The knot is a modification of the "granny," but the additional turn shown in Fig. 10 makes the knot nonslipable, without at the same time giving any appreciable increase in size above the usual weaver's knot.

The particular arrangement enables the movement of the one thread with the rocker having amplified movement to be limited to less than the full or complete movement of 115 the rocker, while at the same time the thread is free to disengage from the rocker when engaged by the tying bill. It is apparent that in order to enable free disengagement with amplified movement, the movement of the 120 rocker must be one or more complete turns unless special mechanism is provided for releasing the thread before the completion of the last turn, and a deepened notch serves this purpose.

What is claimed as new is:—

1. Mechanism for tying a hybrid knot, including a rotary tying bill, means moving with the threads to cross them on one side of the bill, and means moving with the 130

threads on the other side to wind them about each other through a turn and one-half for the purpose specified.

2. In a knitter including a rotary tying bill, means moving with the threads to move them into crossed relation on opposite sides of the bill, means to operate the thread moving means and the bill in sequence, mechanism to impart an amplified movement to one 10 of the thread moving means, the thread moving means including rockers, each having seats for receiving the threads in spaced relation, the seat in the rocker having amplified movement of a depth such that it does not 15 engage the thread until a selected part of its movement has taken place.

3. In a device of the class described, a tying bill, means to position a pair of threads for knotting by the bill, including means 20 moving with the threads at one side of the bill in opposite directions to cross said threads, and means at the other side and moving with the threads to rotate them about each other for substantially a turn and one-half for the purpose specified.

4. In a device of the class described, a tying bill, means to position a pair of threads for knotting by the bill, including means at one side of the bill moving with the threads 30 to cross said threads, means at the other side and moving with the threads to wind them about each other for the purpose specified, the threading moving means including rockers, and means in connection with the last named 35 means for limiting the movement of the

thread therewith to less than the complete movement thereof.

5. A knitter including a rotary tying bill, means for crossing the threads on one side of the bill, means for winding the threads about each other on the other side of the bill, and for positioning them to be simultaneously clamped and cut by the bill during its rotative movement, and means for operating the bill and the crossing and winding means. 40

6. A knitter including a rotary tying bill, means for crossing the threads on one side of the bill, means for winding the threads about each other on the other side of the bill, and for positioning them to be simultaneously 50 clamped and cut by the bill during its rotative movement, means for operating the bill and the crossing and winding means, and means for straining the knot and stripping it from the bill, operated by the operating 55 means.

7. A knitter including a rotary tying bill, means for crossing the threads on each side of the bill, means in connection with one of said means for imparting an amplified movement thereto, thereby to wind the threads about each other and position them to be simultaneously clamped and cut by the tying bill in its rotative movement, and means for operating the bill and the crossing means. 60

Signed at Gastonia, in the county of Gaston and State of North Carolina, this 19th day of June, A. D. 1928.
